UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

CAR-BOLSTER.

No. 825,031.

Specification of Letters Patent.

Patented July 3, 1906.

Application filed August 23, 1905. Serial No. 275,382.

To all whom it may concern:

Be it known that I, ETHAN I. DODDS, a citizen of the United States, residing at Pullman, in the county of Cook and State of Illinois, have invented certain new and useful Improvements in Car-Bolsters, of which the following is a specification.

My invention pertains to car-bolsters; and its principal objects are the production of such a structure which shall provide great strength, which shall be comparatively economical in the cost of manufacture, and the depth of whose sides may be varied to some extent. The bolster has its bellied sides integral with the bottom plate at its central portion, and at the intermediate inclined and horizontal end portion of the sides the bottom is riveted to inturned flanges integral with the sides. At the upper portion of the sides I rivet angle-bars with outwardly-extended flanges, to which may be secured a top plate. In addition, if desired, I may connect the upper parts of the side plates by a channel-bar riveted thereto.

In the accompanying drawings I have illustrated two embodiments of my invention, wherein—

Figure 1 is a longitudinal vertical central section of a body and truck bolster both embodying my invention. Fig. 2 is an enlarged end view of the two bolsters as shown in Fig. 1. Fig. 3 is an enlarged cross-section on the line 3 3 of Fig. 1 as viewed in the direction indicated by the arrows. Fig. 4 illustrates the blank from which the body-bolster is constructed. Fig. 5 illustrates a similar blank from which the truck-bolster is constructed, and Fig. 6 is a perspective view of a modified form of truck-bolster.

Inasmuch as both bolsters are made from blanks which are similar in all respects, a description of the body-bolster blank shown in Fig. 4 will suffice for both constructions.

The body-bolster is made from a rectangular sheet of metal by cutting inwardly from each end two parallel cuts on the lines 11 12. The sheet is then sheared on the lines 13 14 and 14 15, four of each of these cuts being made, as shown in Fig. 4, the point 15 where the line 14 15 meets the line 11 12 being some distance from the point 12. By means of these cuts two tapering pieces of metal are removed from each end, leaving the four recesses shown on the drawings.

In order to provide integral flanges for portions of the lower edges of the parts which are to comprise the side plates of the bolster, I bend up the flanges 16 on the bent lines 17, the same extending from points 12 to the ends of the bolster. The outer longitudinal portions 18 of the sheet 10, which are to form the sides of the bolster, are then folded upon the lines 19 19, joining the points 12 12, so that the sides will be at right angles to the central bottom portion 20. The central strip of the sheet which forms the bottom of the bolster is then bent on the transverse lines 21, so that the portions 22 will be inclined and lie against the inclined portions of flanges 16. The central strip is also bent on the lines 23 to provide the end horizontal portions 24 of the bottom, so as to lie against the horizontal portions of the flanges 16. When the bolster is thus formed to shape, the bottom is riveted to the integral side flanges 16, as shown in Figs. 1, 2, and 3.

It will be evident from this description how the main portion of the truck-bolster is made, since it is constructed identically as set forth above and differs from the body-bolster only in respect to size.

Adjacent to the upper edge of each side of the body-bolster I rivet the angle-bars 25, with their flanges extending outwardly, the bars being substantially the same length as the body-bolster. As spacing means for the ends of the bolster I provide dish-shaped members 26, with their flanges extending outwardly, the same being riveted to the sides and bottom of the bolster, the rivets passing also through the angle-bars 25 and the flanges 16. To these upper outwardly-extended angle-bars I rivet a top tension-plate 27, as is shown in Figs. 1, 2, and 3. The angle-bars 28, secured to the sides of the truck-bolster, extend over only a part of the length of the bolster, as is shown in Fig. 1, and to these angle-bars I rivet a compression-plate 29. At the ends of the bolster the dish-shaped members 30 act as spacing means to hold the sides apart and at the same time join them together, these members being riveted to the sides and bottom of the bolster, as shown in Figs. 2 and 3. It will be clear that these upper angle-bars may be fastened to the sides, so that their outwardly-extended flanges would be some distance above the upper edges of the sides. By so doing I may vary the depth of the sides of the bolster and

strength of the same and am enabled to use a standard size bolster for cars which require such structures of different strengths or depths. The strength of the bolster may also be varied by using angle-bars of different strengths and sizes.

The modified form of bolster shown in Fig. 6 is in all respects like the one illustrated in Figs. 1, 2, and 3, except that the angle-bars 10 28° at the upper edges of the sides are somewhat shorter than the corresponding parts shown in the other figures. The top plate 29' corresponds to the length of these angle-bars, and in addition to this top member I 15 employ a channel-bar 31, with its flanges extending upwardly and riveted to the sides adjacent to their upper edges. It will be seen from this construction that I secure an especially strong structure, since the integral 20 flanges of this channel-bar 31 are riveted directly to the sides.

While I have herein shown and described the preferred embodiments of my improvements, it is to be understood, however, that 25 the details may be modified without departing from the invention, and accordingly I do not limit myself to these details, except to the extent that they are made the subject-matter of specific claims.

30 This patent is intended to embrace only so much of the disclosure made herein as is covered by the claims.

I claim—

1. A car-bolster, having side plates, a bottom plate integral with said side plates for a 35 portion of its length, and angle-bars riveted to said side plates adjacent to their upper edges, substantially as described.

2. A car-bolster having side plates, a bottom plate integral with said side plates for a 40 portion of its length, angle-bars riveted to said side plates adjacent to their upper edges, and a top plate riveted to said angle-bars, substantially as described.

45 3. A car-bolster having side plates, a bottom plate integral with said side plates for a portion of its length, and angle-bars with outwardly-extended flanges riveted to said side plates adjacent to their upper edges, substantially as described.

50 4. A car-bolster having side plates, a bottom plate integral with said side plates for a portion of its length, an angle-bar with outwardly-extended flanges riveted to each of 55 said side plates, and a top plate riveted to said outwardly-extended flanges, substantially as described.

5. A car-bolster having side plates, a bottom plate integral for a portion of its length 60 with said side plates, inwardly-extended flanges along a portion of the lower edge of each side plate, said bottom plate being riveted to said flanges, and an angle-bar riveted to each side plate adjacent to its upper edge, 65 substantially as described.

6. A car-bolster having side plates, a bottom plate integral with said side plates for a portion of its length, each side plate having an inwardly-extended flange along a portion of its lower edge, said bottom plate being riveted to said flanges, an angle-bar riveted to each side plate adjacent to its upper edge, and a top plate riveted to said angle-bars, substantially as described. 70

7. A car-bolster having side plates, a bottom plate integral with said side plates for a portion of its length, each side plate having an integral inwardly-extended flange along a portion of its lower edge, said bottom plate being riveted to said flanges, and an angle-bar riveted to each side plate adjacent to its upper edge, substantially as described. 75

8. A car-bolster having side plates, a bottom plate integral with said side plates for a portion of its length, each side plate having an integral inwardly-extended flange on a portion of its lower edge, said bottom plate being riveted to said flanges, an angle-bar riveted to each side plate adjacent to its upper edge, and a top plate riveted to said angle-bars, substantially as described. 80

9. A car-bolster having side plates, a bottom plate integral with said side plates for a portion of its length, each side plate having an integral inwardly-extended flange on a portion of its lower edge, said bottom plate being riveted to said flanges, and an angle-bar with an outwardly-extended flange riveted to each side plate adjacent to its upper edge, substantially as described. 85

10. A car-bolster having side plates, a bottom plate integral with said side plates for a portion of its length, each side plate having an integral inwardly-extended flange on a portion of its lower edge, said bottom plate being riveted to said flanges, an angle-bar with an outwardly-extended flange riveted to each side plate, and a top plate riveted to the outwardly-extended flanges of said angle-bars, substantially as described. 90 100

11. A car-bolster having side plates, a bottom plate integral with said side plates for a portion of its length and fastened to said side plates for another portion of its length, and a channel-bar having its flanges fastened to 95 said side plates, substantially as described. 110

12. A car-bolster having side plates, a bottom plate integral with said side plates for a portion of its length, each side plate having an inwardly-extended flange along a portion of its lower edge, said bottom plate being riveted to said flanges, and a channel-bar riveted to said side plates adjacent to their upper edges, substantially as described. 120

13. A car-bolster having side plates, a bottom plate integral with said side plates for a portion of its length, each side plate having an integral inwardly-extended flange along a portion of its lower edge, said bottom plate being riveted to said flanges, and a channel- 130

bar riveted to said side plates adjacent to their upper edges, substantially as described.

14. A car-bolster having side plates, a bottom plate integral with said side plates for a portion of its length, each side plate having an integral inwardly-extended flange along a portion of its lower edge, said bottom plate being riveted to said flanges, an angle-bar with an outwardly-extended flange riveted to each of said side plates, a top plate riveted

to the outwardly-extended flanges of said angle-bars, and a channel-bar, the flanges of said channel-bar being riveted to said side plates, substantially as described.

Chicago, Illinois, August 19, A. D. 1905.
